(57) **CLAIM**

The ornamental design for a bottle as shown and described.

DESCRIPTION

FIG. 1 is a top perspective view of a first embodiment of a bottle;

FIG. 2 is a front view thereof;

FIG. 3 is a side view thereof;

FIG. 4 is a rear view thereof;

FIG. 5 is a side view thereof, opposite the side view of FIG. 3;

FIG. 6 is a top view thereof;

FIG. 7 is a bottom view thereof;

FIG. 8 is a top perspective view of a second embodiment of a bottle;

FIG. 9 is a front view thereof;

FIG. 10 is a side view thereof;

FIG. 11 is a rear view thereof;

FIG. 12 is a side view thereof, opposite the side view of FIG. 10;

FIG. 13 is a top view thereof; and,

FIG. 14 is a bottom view thereof.

Broken lines illustrate structures or features that form no part of the claimed design. The dot-dash broken lines represent boundaries of the claimed design; the dot-dash broken lines themselves form no part of the claimed design.

1 Claim, 12 Drawing Sheets
